18 Claims. (Cl. 179—16)

The present invention relates to a circuit arrangement for transmitting impulses by means of alternating current over repeatered lines in telephone systems.

5 The known arrangement in which the impulses are taken up by a receiving relay tuned to the frequency of the alternating current used have the disadvantage that a relatively large amount of energy is necessary to operate the receiving relay, further the receiving relay is only suitable for a particular frequency and finally the length of the impulse received is subject to considerable variations on account of the varying electrical properties of the line between the sending and receiving station.

10 The invention makes it possible to use a sensitive receiving relay which responds to very little energy and which moreover is independent of the frequency of the alternating current. At the same time the duration of the impulse received is made positively dependent upon the impulse generated at the sending station.

15 According to the invention this is achieved in that switching means are provided at the sending station which during the transmission of an impulse first transmits half waves in the one direction and thereupon half waves in the other direction over the line.

20 The attached Figs. 1, 1a-1c represent an embodiment of the invention, all unimportant details of the circuit being omitted.

25 If in Fig. 1 the connecting line VL is seized over a preceding switch the seizing relay C energizes over the test lead c. Relay C by means of its contact 1c closes the following circuit for the slow-to-release relay U: earth, contacts 1c and 2a, the winding of relay C, battery and earth. Relay U energizes. It opens its contacts 3u and 4u and closes its contacts 5u and 6u. The rectifier GL is thus connected across the leads of the line. Relay C causes a seizing impulse to be transmitted over the connecting line VL to the incoming end of the connecting line by locally energizing a second winding (not shown) of the impulse receiver relay A. Relay A transmits the alternating current impulse further at its contacts 7a and 8a in the same manner as the setting impulses which are now to be described.

30 The setting impulses proceeding from the preceding group selector are taken up by the winding I of the receiving relay A in the a-lead. During the impulsive, earth is applied impulsively to the a-lead in the group selector. Relay A operates in response to the impulsive. As soon as relay A energizes the source WQ of alternating

35 current is connected to the connecting line over contacts 7a and 8a. On account of the rectifier GL connected across the leads of the line over contacts 5u and 6u, the half waves in the one direction are restrained from passing to the repeater winding. For these half waves the rectifier acts as a shunt. Thus at first only the half waves in one direction are transmitted over the connecting line VL. The rectifier is assumed to have such a polarity that in the first place 40 only the positive half waves are transmitted over the connecting line. In response to this the polarized relay J at the incoming end of the line operates its armature and in consequence closes contact j. Contact j transmits earth impulses 45 over the a-lead.

50 When the receiving relay A energizes at the outgoing end of the line, the circuit for relay U is broken at contact 2a. Relay U releases after a given time. The release period of this relay can be adjusted, for example so that assuming an impulse of 60 milliseconds duration it releases after 30 milliseconds. When relay U releases the contacts 5u and 6u are opened and the contacts 3u and 4u closed. The rectifier GL is now connected 55 in shunt across the repeater winding in the reverse sense to that in which it was previously connected. Thus, since contacts 7a and 8a are still closed the positive half waves which previously were transmitted over the line are now suppressed 60 and the half waves in the opposite negative direction are transmitted over the line. By means of this impulse the polarized receiving relay J is again operated and this terminates the impulse. With alternating current of 50 cycles per second 65 and an impulse length of 60 milliseconds there will be transmitted over the line two positive half waves and subsequently two half waves in the opposite direction as shown in Fig. 1c.

70 The release period of relay U can of course also be adjusted so that using an alternating current of 50 cycles three half waves are transmitted over the line first in the one direction and then only one half wave in the other direction. The release period of relay U must amount to 50 milliseconds in this case.

75 Fig. 1a shows an arrangement in which the relay U of Fig. 1 which switches over the rectifier GL does not release on the reception of an impulse, but is energized. In order to produce a corresponding operation with this arrangement it is only necessary to delay the energizing period 80 of relay U in a corresponding manner.

85 Fig. 1b shows an embodiment of the invention in which the polarized receiving relay J of Fig. 55

1 is replaced by two normal direct current relays each having a rectifier connected in parallel.

The mode of operation of the arrangement is that the half waves transmitted over the line on the commencement of an impulse operate one of the relays, for example relay J1 while these half waves are prevented from operating the second relay, namely relay J2, by means of the rectifier GL2 connected in parallel with it and 10 through which these half waves pass.

The half waves in the opposite direction which are received at the end of the impulse then operate relay J2 in a corresponding way since the rectifier GL2 connected in parallel with this 15 relay blocks the passage of these half waves. They pass over the rectifier GL1 which is connected in parallel with relay J1 so that it passes the half waves in this direction.

The impulses are extended by relay J1 closing 20 its contact j1 at the commencement of each impulse and applying earth to the a-lead. The impulse is terminated independently of the release of relay J1 by relay J2 opening its contact j2 at the end of the impulse and thereby disconnecting earth from the a-lead.

If, for the impulsing, frequencies other than 50 25 cycles and in particular higher frequencies are used, the operation becomes increasingly efficient with increasing frequency, for as may be seen from Fig. 1c the receiving relay receives an increasing number of rectified waves for each impulse, so that the pauses between the half waves which must be bridged by the release becomes increasingly smaller.

The principle upon which the invention is 30 based is not only applicable for alternating current selection but also for special purposes lying outside the scope of alternating current dialling, namely the characterization of different traffic directions over repeatered lines.

Figs. 2, 3, 4, and 5 represent embodiments for the characterizing of different traffic directions.

Fig. 2

The connecting line VL can be seized over 45 various approaches. The testing leads of these approaches are indicated by c1—c5. These approaches correspond to the incoming ends of the connecting line in the directions 1—5.

On seizing the connecting line over the approach c1 from a preceding switch a short seizing impulse lasting approximately 60 milliseconds is transmitted over the connecting line. As is shown in Fig. 3a this impulse comprises full-wave alternating current.

If the connecting line VL is seized over the approach c2 again an alternating current impulse for characterizing the traffic direction 2 is transmitted over the connecting line. Fig. 3b shows that this impulse comprises a train of half waves in a particular direction which is indicated as positive.

If the connecting line is seized over the approach c3 an alternating current impulse for characterizing the traffic direction 3 is sent over the connecting line and as may be seen from Fig. 3c consists of a train of half waves in the opposite negative direction.

If the connecting line VL is seized over the approach c4 then as shown in Fig. 3d on the commencement of the seizing impulse a number of positive half waves are transmitted and then one half wave in the negative direction.

If the connecting line is seized over lead c5 a number of half waves in the negative direction 75 are transmitted for characterizing the direction

5 on the commencement of the impulse and these are followed by a half wave in the positive direction (Fig. 3e).

The circuit arrangements will now be described in detail.

On seizing the connecting line over the testing lead c1, relay C1 is energized. Relay C1 completes the following circuit for relay A: earth, contact 1c1, winding II of relay A, contact 12d, battery and earth. Relay A energizes and connects the source WQ of alternating current to the repeater Ue1 over contacts 3a and 4a. This alternating current is transmitted unrectified. It passes over the connecting line VL and the repeater Ue2 to relays J1 and J2 on account of the rectifiers GL1 and GL2 connected in the appropriate sense in parallel with these relays. Relay J1 is energized by one set of alternating half waves of the alternating current and relay J2 by the other half waves. Relays J1 and J2 do not release during the pauses between the individual half waves. The pauses when using the normal frequency for alternating current dialling of 50 cycles amount to 10 milliseconds. The rectifiers connected in parallel with each impulse receiving relay constitute a short-circuit for the relays by means of which impulses of the length mentioned are bridged. The alternating current impulse is terminated in that relay A closes the following circuit for relay D at the outgoing end of the 30 line: earth, contact 6a, the windings of relay D, battery and earth. Relay D makes a delayed operation after about 60 milliseconds so that the impulse is given a sufficient duration. Relay D breaks the circuit of relay A by opening its contact 12d. Relay A releases and thereby terminates the impulse. Relay D holds up after relay A has released in the following circuit: earth, contacts 7d and 8c1, the windings of relay D, battery and earth.

At the incoming end of the line relays J1 and J2 are energized by the seizing impulse as already mentioned. The following circuit is accordingly closed for relay Z: earth, contacts 64g, 42j1, 44y, 50j2 and 52x, the winding of relay Z, battery and earth. When relays J1 and J2 energize the following circuit is also closed for the seizing relays B and E: earth, contact 69j1 and in parallel 70j2, and 68e, the winding of relay B, contacts 66b and 65e, resistance Wi, battery and earth. By opening its contact 66b relay B breaks the short-circuit for relay E which now energizes in series with relay B. After relays J1 and J2 have released the relays B and E hold up in the following circuit: earth, contact 71b, the winding of relays B and E, resistance Wi, battery and earth. Relay Z holds up at the end of the impulse independently of relays J1 and J2 in the following circuit: earth, contacts 58e and 51z, the winding of relay Z, battery and earth. Relay Z closes its contact 59z and thus seizes the outlet 1. In this circuit relay G also energizes. Relay G by opening contact 64g prevents any further influencing of the switching means provided for characterizing the outlet by the further setting 65 impulses transmitted for the establishment of the connection.

The further impulses for setting the switches energize winding I of relay A in the outgoing end of the line. The impulses are transmitted 70 as full wave alternating current impulses over the connecting line VL through the closing of contacts 3a and 4a. At the incoming end relays J1 and J2 are energized by the impulses and thus the impulses are transmitted for example over the 75

a-lead to the succeeding switches in a manner which is of no particular interest.

The release is effected in the manner which is usual when using alternating current dialling by means of a long releasing impulse. This is initiated by the release of the seizing relay C1, when relay A is energized for a prolonged time over winding II in a manner which is not indicated. Contacts 3a and 4a transmit a prolonged 10 alternating current impulse over the connecting line VL. Relays J1 and J2 at the incoming end of the line are accordingly energized for a prolonged period. At contacts 69j1 and 70j2 relay B is short-circuited and releases. Relay V also 15 breaks the locking circuit of relay E which lies in parallel with it. Relay E releases and initiates the release of the locking circuit of relay Z and of the switching means in the repeater Ue2.

When the connecting line VL is seized over the 20 lead c2 by a preceding switch relays C2 and C1 energize in series. Relay C1 completes a circuit for winding II of relay A. Relay A applies alternating current to the connecting line over contacts 3a and 4a. In addition relay A connects 25 relay D over contact 6a, the latter again interrupting the seizing impulses. Relay C2 closes its contact 13c2 and thus connects the rectifier GL across the leads of the line. This establishes a short-circuit for the negative half waves of alternating current, the circuit for which is as follows: source WQ of alternating current, contacts 3a, 32d, 13c2, 14c3, 20k, 16m, rectifier GL, resistance Wr, contacts 22m, 24k, 28c3, and 4a, back to the source WQ. The positive half-waves 30 pass over the winding of the repeater Ue1 and thus over the connecting line VL to the repeater Ue2 at the incoming end of the line.

These halfwaves pass over relay J2, the rectifier GL1 and back to the secondary winding of 40 the repeater Ue2. The rectifier GL2 connected in parallel with relay J2 blocks the passage of these half waves. Relay J2 closes the following circuit: earth, contacts 64g, 40j1, 41j2, the winding of 45 relay Y, battery and earth. At the same time relays B and E are energized over contact 70j2 and hold up throughout the duration of the call. After the release of relay J2 relay Y locks up in the following circuit: earth, contacts 43e, 48y and 13q, the winding of relay Y, battery and 50 earth. Relay Y closes its contact 60y and thus seizes the outlet 2. In the seizing circuit relay G energizes again. Relay G by opening contact 64g prevents the relay provided for characterizing the direction from being influenced by the further 55 impulses.

The impulse sending and releasing takes place in the manner already described.

When the connecting line VL is seized over the lead c3 relays C3 and C1 are energized at the 60 outgoing end of the line. Relay C1 energizes relay A. By means of its contacts 3a and 4a relay A applies alternating current to the winding of repeater Ue1. Contact c3 connects rectifier GL across the two leads of the line but at this time in the reverse direction to that when characterizing the outlet 2. The rectifier therefore constitutes a shunt in respect of the positive half waves (Fig. 3c). The shunt circuit is as follows: source WQ of alternating current, 65 contacts 4a, 33d, 18c3, 20k and 16m, the rectifier GL, resistance Wr, contacts 22m, 24k, 27c3 and 3a and back to the source WQ of alternating current. Only impulses in the negative sense pass over the windings of the repeater Ue1. These 70 at the incoming end of the line serve to energize

relay J1 in the following circuit: secondary repeater winding Ue2, winding of relay J1, the rectifier GL2 and back to the repeater windings. The rectifier GL1 in parallel with relay J1 blocks the passage of the incoming half waves in this case. Relay J1 completes the following circuit: earth, contacts 64g, 42j1, 44y, and 45j2, the winding of relay X, battery and earth. Moreover relay J1 energizes the seizing relays B and E over contact 69j1. After the release of relay 10 J1 relay X holds up in the following circuit: earth, contacts 47e, 46x and 72h, the winding of relay X, battery and earth. Relay X through closing its contact 61x, seizes the outlet 3. In this seizing circuit relay G is energized again. 15 The further operations during the establishment of the connection takes place as already described.

When the connecting line VL is seized over lead c4 relays C4 and C1 are energized in series. 20 Relay C1 energizes relay A. Relay A again applies alternating current to the connecting line. At the same time the relay D which is very slow to energize energizes and terminates the seizing impulse. Relay C4 connects the rectifier GL 25 across the leads of the line so that it constitutes a short-circuit for the half waves in the negative direction. The short-circuit is as follows: source WQ of alternating current, contacts 3a, 32d, 15c4, 14c3, 20k and 16m, the rectifier GL, 30 resistance Wr, contacts 22m, 24k, 28c3, and 4a and source WQ of alternating current. Thus only the positive half waves now pass over the connecting line (Fig. 3d). Relay C4 on energizing closed the following circuit for relay K: 35 earth, the winding of relay K, contacts 9a, 10c4 and 11d, battery and earth. Relay K is slightly slow to operate; the time which it takes to operate is adjusted so as to amount to approximately 40 ms. Relay K connects the rectifier GL in the 40 opposite sense across the two leads of the line after the expiry of this period. Since relay D which terminates the impulse energizes only after about 60 ms. i. e., after relay K, the rectifier GL now forms a shunt for the positive half waves 45 (Fig. 3d). This shunt circuit runs as follows: source WQ of alternating current, contacts 4a, 21k, 16m, the rectifier GL, resistance Wr, contacts 22m, 25k and 3a and source WQ of alternating current. Thus following shortly after 50 the transmission of the positive half waves a series of negative half waves are transmitted over the line.

At the incoming end relay J2 is energized by the positive half waves and thereupon J1 is energized by the negative half waves. Relay J2 completes a circuit for relay Y at contact 41j2. Relay Y takes about 15 ms. to energize. Therefore 55 since relay J2 is energized for a longer time it can energize in this case. Relays B and E are 60 energized at the same time by relay J2. As already described relay Y locks up over contact 48y independently of relay J2. The negative half waves following the positive half waves energize relay J1 in the incoming repeater Ue2. Thus the 65 following circuit is established for relay Q: earth, contacts 64g, 42j1, and 49y, the winding of relay Q, battery and earth. Relay Q after energizing locks up in the circuit: earth, contacts 53e and 53q, the winding of relay Q, battery and earth. 70 Through the closing of contact 62g the outlet 4 is seized. Relay Q breaks the locking circuit for relay Y by opening its contact 73q.

On seizing the connecting line VL over the approach c5 relays C5 and C1 are energized in 75

series. Relay C1 completes a circuit for winding II of relay A. Relay A applies alternating current to the connecting line VL. Relay C5 connects the rectifier GL across the leads of the line in such a way that it constitutes a short-circuit for the positive half waves (Fig. 3e). The short-circuit is as follows: source WQ of alternating current, contacts 4a, 33d, 19c5, 20k and 16m, the rectifier GL, resistance Wr, contact 22m, 24k, 26c5 and 3a and source WQ of alternating current. Thus the negative half waves are now transmitted over the line VL. When relay C5 energizes the following circuit is set up for relay M: earth, the winding of relay M, contacts 29a, 30c5 and 31d, battery and earth. Relay M takes the same time to energize as its relay K, i.e., about 40 ms. It reverses the connection of the rectifier GL after a number of negative half waves have been transmitted over the line in such a way that now a short-circuit is provided for these half waves and the half waves in the positive sense are transmitted over the connecting line. The short-circuit for the negative half waves established by relay M is as follows: earth, contacts 3a and 17m, the rectifier GL, resistance Wr, contacts 23m and 4a and source WQ of alternating current.

At the incoming end of the line relay J1 is energized by the negative half waves occurring at the commencement of the impulse. Relay J1 completes a circuit for relay X over contact 42f1. Like relay Y it takes approximately 15 ms. to energize. Relay J1 also energizes relays B and E over contact 69j1. After relay J1 has released relay X locks up as already described over its contact 46x. As soon as a positive half wave is received after the negative half waves have been transmitted relay J2 is energized. The following circuit is now completed for relay H: earth, contacts 64g, 42f1, 44y, 50j2, 51x, the winding of relay H, battery and earth. After relays J1 and J2 have energized relay H locks up in circuit: earth, contacts 55e and 56h, the winding of relay H, battery and earth. Relay H closes contact 63h and thus seizes the outlet 5. At the same time relay H breaks the locking circuit for relay X at contact 72h.

It may be mentioned at this point that instead of the relays J1 and J2 which are polarized by the rectifiers GL1 and GL2 connected in parallel with them, two electromagnetically polarized receiving relays can be used.

It may also be mentioned that the principle of the invention namely, to characterize a number of traffic directions by alternating current of a prescribed frequency can of course be utilized for the characterizing of a greater number of outlets than is shown in the embodiments 2 or 3a—3d. Thus for example in order to characterize six different directions control relays must be provided at the outgoing end of the line or by auxiliary relays at the incoming end of the line which, with reference to the half waves shown in Fig. 3d which are first positive and then negative in sense, transmit and convert respectively further trains of positive waves. A seventh direction may then be characterized in the same way by adding a train of negative half waves to the succession of waves shown in Fig. 3e. Naturally a larger interval of time will then be required for the seizing impulse.

Figs. 4 and 5 show embodiments for characterizing different traffic directions. As regards the fundamental mode of operation these arrangements do not differ from those of Fig. 2 and Figs.

3a—3e. The arrangement according to Fig. 4 shown represents an arrangement which differs merely at the outgoing end of the connection line and serves to premagnetize the repeater Uel in a definite sense before each characterizing impulse. This is necessary because the residual magnetism still remaining in the repeater from the release impulse of a previous call may have the same direction as the first half waves of the following characterizing impulse. The latter would thus bring the magnetization of the repeater within the region of saturation so that for want of sufficient variation of field in the secondary winding of the repeater only impulses of insufficient potential would be induced. For this reason the arrangement shown in Figs. 4 and 5 have been evolved whereby shortly before each seizing impulse a temporary premagnetizing of the outgoing repeater in the direction opposite to that of the subsequent half waves to be transmitted takes place.

According to Fig. 4 the premagnetizing of the outgoing repeater takes place with direct current from the battery and in Fig. 5 by means of rectified direct current from the rectifier already present.

In Figs. 4 and 5 for the sake of simplicity an arrangement is shown in which the premagnetization of the outgoing repeater does not take place before all the characterizing impulses but only before the seizing impulses which characterize the directions 4 and 5 (Figs. 3d and 3e). It indicates, however, to the technician the manner in which corresponding premagnetization prior to the other characterizing impulses may be obtained.

Fig. 4: It may be stated for the sake of clarity that two rectifiers GR1 and GR2 are shown in place of a single rectifier. These can, however, be replaced by a single rectifier in the same manner as in Fig. 5, the circuit being modified correspondingly.

If the connecting line VL is seized over the approach c4, the relays C4 and C1 in series energize. The relay C1 switches on relay A over contact 4c1 which applies alternating current WQ to the primary windings of the outgoing repeater Uel over its contacts 3a and 4a. Previously a direct current circuit was completed over the primary winding of the repeater Uel over contacts 34c4 and 35c4: earth, battery, contacts 34c4, 36c5 and 2a, the primary windings of the repeater Uel, contacts 5a, 39c5 and 35c4 and earth. This direct current premagnetizes the repeater Uel in a definite sense this being opposite to that of the positive half waves which are now transmitted. The magnetizing circuit is broken by the energizing of relay A which opens its contacts 2a and 5a. At the same time contact 81a is closed so that the rectifier GR1 is connected across the leads of the line by way of contacts 32d, 81a, 20k, 24k and 15c4. The rectifier GR1 blocks the positive half waves while transmitting the negative half waves. Thus at first only the positive half waves are transmitted over the repeater Uel and the connecting line VL. Since after a time the slow operating relay K is energized in the following circuit: earth, the winding of relay K, contacts 9a, 10c4 and 11d, battery and earth, the rectifier GR1 is now connected via contacts 21k and 25k in the reversed sense between the leads of the line. The result of this is that now instead of the positive half waves negative half waves are transmitted over the repeater Uel and the connecting line. The very

slow to operate relay K which is connected by relay A at contact 6a terminates the impulse.

If the connecting line VL is seized over the bridge c5 the relays C5 and C1 disposed in series energize together. Relay C1 switches on relay A over contact 1c1. Relay C5 completes the following direct current circuit over primary winding of the outgoing repeater Ue1: earth, battery, contacts 38c5, 5a, the primary windings of the repeater Ue1, contacts 2a and 37c5 and earth. The direction of this direct current which serves to pre-magnetize the repeater Ue1 is opposite to that of the following half waves of the seizing impulse. The direct current circuit is broken by the energizing of relay A which opens its contacts 2a and 5a. At the same time contact 80a is also closed so that the rectifier GR2 is connected across the line by way of contacts 33d, 80a, 16m, 22m, and 19c5. The rectifier GR2 passes the positive half waves of alternating current while the negative half waves are transmitted over the repeater Ue1 and the connecting line VL. Since after a certain time relay M energizes in the following circuit: earth, the winding of relay M, contacts 29a, 30c5 and 31d, battery and earth, the contacts 16m and 22m are opened and contacts 17m and 23m closed. The rectifier GR2 is now disposed between the leads of the line in the positive sense. The result of this is that now instead of the negative half waves one or more positive half waves are transmitted over the rectifier Ue1 and the connecting line VL. At the incoming end of the connecting line the outlet 6 is characterized by a succession of negative and positive half waves. The characterizing impulse is terminated by the very slowly energizing relay D as has been frequently described before.

Fig. 5: After the connection line VL is seized over the approach c4 the relays C4 and C1 which are disposed in series energizing together. Relay C4 closes its contacts 34c4 and 35c4 and thus applies the source WQ of alternating current to the leads of the line over the high resistances of, for example, 5,000 ohms each. Since contacts 12c4, 15c4 and 28c4 are closed at the same time, the rectifier GL is disposed across leads of the line in such a way that the positive half waves flow through the rectifier GL while negative half waves pass over the primary winding of the repeater Ue1. The circuit for the positive half waves over the repeater is as follows: source WQ of alternating current, resistance of 5,000 ohms, contacts 34c4, 36c5, 2a, 32d, 12c4, 18a1, 15c4, and 16m, the rectifier GL resistance Wr, contacts 22m, 84a1, 28c4, 5a, 39c5, 35c4, resistance of 5,000 ohms and source WQ of alternating current. The negative half waves passing over the primary windings of the repeater Ue1 which on account of the high resistances connected to the alternating current source are not strong enough to cause effective impulses to be transmitted over the connecting line magnetize the repeater Ue1 in a particular sense which is opposed to that of the following half waves. The premagnetizing circuit is broken as soon as relay C1 has energized relay A over contact 1c1. Relay A breaks the above circuit by opening its contacts 2a and 5a. By closing contacts 3a and 5a the source WQ is again connected to the leads of the line this time, however, over small resistances for example of 1,000 ohms each. In parallel with relay A, relay A1 energizes. This closes its contacts 19a1 and 85a1. The rectifier GL is now connected in the opposite sense to that in which it was previously connected between the leads

of the line. It thus constitutes a short-circuit in respect of the negative half waves: source WQ of alternating current, resistance of 1,000 ohms, contacts 4a, 13c5, 22k, 19a1, 15c4 and 16m, rectifier GL, resistance Wr, contacts 22m, 85a1, 25k, 27c5, and 3a, resistance of 1,000 ohms and source WQ of alternating current. The positive half waves which pass over the primary windings of the repeater Ue1 induce impulses of sufficiently high potential to operate the receiving relay at the incoming end of the connecting line VL. Relay A after a certain time operates relay K over earth, the winding of relay K, contacts 9a, 18c4 and 11d, battery and earth. The contacts 21k and 24k are closed and thus the rectifier GL is now disposed across the leads of the line in such a way that the positive half waves pass over the rectifier while negative half waves pass over repeater Ue1 and the connecting line VL. A train of positive half waves and a subsequent train of negative impulses characterizes the outlet 4 as may be seen from Fig. 3d. The characterizing impulse is terminated by the energizing of relay D as in Figs. 3 or 4.

If the connecting line VL is seized over the bridge c5 the serially arranged relays C5 and C1 energize together. Relay C5 closes its contacts 31c5 and 38c5 and thereby connects the source WQ of alternating current to the leads of the line over the high resistance of 5,000 ohms. Relay C5 also closes its contacts 19c5, 20c5 and 26c5 so that the rectifier GL is bridged across the leads of the line, this time in such a way that the negative half waves pass over the rectifier GL. The circuit for the negative half waves is as follows: source WQ of alternating current, resistance of 5,000 ohms, contacts 38c5, 5a, 33d, 14c4, 18a1, 20c5 and 16m, the rectifier GL resistance Wr, contacts 22m, 84a1, 29c4, 2a and 37c5, resistance of 5,000 ohms and source WQ of alternating current.

On account of the high resistance connected in front of the source of alternating current the positive half waves transmit no effective impulses over the line VL. They are, however, sufficient to premagnetize repeater Ue1. The magnetizing circuit previously mentioned is broken as soon as relay C1 energizes relay A over contact 1c1. Relay A breaks the circuit by opening its contacts 2a and 5a. Through the closing of contacts 3a and 4a the source WQ of alternating current is again connected to the leads of the line, this time, however, over smaller resistances for example each of 1,000 ohms. Since relay A1 also energizes in parallel with relay A and opens contacts 18a1 and 84a1 and closes its contacts 19a1 and 85a1 the rectifier GL is now connected across the leads of the line in the opposite sense to that of its previous connection. It constitutes a short-circuit for the positive half-waves: source WQ of alternating current, resistance of 1000 ohms, contacts 3a, 19c5, 22k, 19a1, 20c5, 16m, rectifier GL, resistance Wr, contacts 22m, 85a1, 25k, 26c5 and 4a, resistance of 1,000 ohms and source WQ of alternating current. The negative half waves are transmitted over the repeater Ue1. These induce impulses in the secondary winding which are transmitted over the connecting line to the incoming end and there operate the receiving relay. After a given time relay M energizes over: earth, the winding of relay M, contacts 29a, 30c5 and 31d, battery and earth. Relay M opens its contacts 16m and 22m and closes its contacts 17m and 23m. The rectifier GL is now connected once more in the reverse sense between the leads

of the line so that the negative half waves pass over the rectifier and the positive half waves over the repeater U_{el} . A train of negative half waves followed by a positive impulse serves to characterize the outlet 5 as shown in Fig. 3e. The characterizing impulse is terminated by relay D as already described.

What is claimed is:

1. An impulse sender, including means for generating alternating current, a rectifier for blocking the transmission of either the positive or the negative portion of said alternating current, and impulse operated means controlling said first means and said rectifier to transmit one or more spaced apart impulses each comprising the positive portion only of the current generated by said first means for an interval of time followed by the negative portion only of the current generated by said first means for an interval of time.
2. In a signalling system, a line, means responsive to spaced apart impulses and effective to impress alternating current upon said line continuously during each impulse, change over means having two positions and occupying each of said positions at some time during each impulse, and means for preventing the flow of current in one direction over said line when said last means is in one position and for preventing the flow of current in the opposite direction over said line when said last means is in the other position.
3. In a signalling system, a line circuit, means responsive to spaced apart impulses and effective to impress alternating current upon said line circuit continuously during each impulse, a rectifier connected in said line circuit in one sense during the first portion of each impulse thereby to prevent the transmission thereover of current in one direction, and means operated a predetermined interval of time after the beginning of each impulse to connect said rectifier in the line circuit in the opposite sense thereby to prevent the transmission thereover of current in the opposite direction during the remainder of the impulse.
4. In a signalling system, electromagnetic means operated periodically by a succession of spaced apart primary impulses of current, a line, means for transmitting over said line, during each of said primary impulses, a succession of secondary impulses of direct current, and means controlled by said first means for varying the polarity of said secondary impulses thereby to divide said succession of secondary impulses into a plurality of trains, the consecutive ones of said trains comprising secondary impulses of different polarity.
5. A signalling system as claimed in claim 4, wherein said secondary impulses comprise either the positive or negative portion of the current produced by an alternating current generator.
6. An impulse repeater, including a source of alternating current, means operated by received impulses to derive pulsating direct current of either positive or negative polarity from said alternating current and to transmit impulses corresponding to the received impulses, each transmitted impulse comprising a plurality of pulsations of said direct current, and means controlled by said last means causing certain of said plurality of pulsations to be of one polarity and certain to be of the opposite polarity.
7. An impulse repeater as claimed in claim 6, wherein the transmitted impulses pass through

the primary winding of a transformer, and wherein the first pulsation of a transmitted impulse may be of either positive or negative polarity, means for passing current through the primary winding of said transformer prior to said first pulsation to premagnetize said transformer in a sense opposed to the magnetization thereafter produced by said first pulsation.

8. In combination, means for generating alternating current, means for deriving pulsating direct current of either positive or negative polarity from said alternating current, a transformer upon whose primary winding said pulsating direct current is impressed at spaced intervals, the first pulsation of said current impressed upon said primary winding at said intervals being of positive polarity at times and of negative polarity at other times, and means for premagnetizing said transformer prior to each interval, said premagnetization being in one direction or in the opposite direction depending upon the polarity of the first pulsation of said current to follow thereafter.

9. A signalling system, including two sources of alternating current, a rectifier for blocking the transmission of either the positive or the negative portion of the alternating current from either source, and means controlling said sources and said rectifier to transmit impulses each including pulsating direct current of one polarity from one source for an interval of time followed by pulsating direct current of the opposite polarity from the other source for an interval of time.

10. In a signalling system as claimed in claim 9, a transformer over whose primary winding said impulses are transmitted, and signal receiving means connected to the secondary winding of said transformer and actuated only by the pulsating direct current of said other source, the pulsating direct current from said one source serving only to premagnetize the transformer in a given sense in preparation for said pulsating direct current from said other source.

11. In a signalling system, a transformer, signal receiving means connected to the secondary winding of said transformer, means for generating alternating current and for deriving pulsating direct current of either positive or negative polarity therefrom, means controlling said last means first to impress pulsating direct current of a particular value and of either polarity upon the primary winding of said transformer to premagnetize the same and then to impress upon said primary winding pulsating direct current of a different value and of the opposite polarity to that first impressed, thereby to actuate said signal receiving means.

12. In a signalling system, a signalling line, a transformer dividing said line into two inductively associated sections, a source of direct current connected to one of the sections, current from said source thereby flowing through the primary winding of said transformer in a particular direction to premagnetize said transformer, means for disconnecting said source and impressing alternating current upon said one section for an interval of time, a rectifier effective only during said interval of time and, during said interval of time, effective first to prevent the flow of current through the primary winding of said transformer in said particular direction while permitting it to flow in the opposite direction and then to prevent the flow of current through said primary winding in the opposite direction while permitting it to flow in said particular di-

rection, and a polarized device connected to the other line section and controlled by the rectified alternating current according to the direction of its flow through said primary winding.

5 13. In a signalling system, a signalling line including two inductively associated line sections, a polarized signal receiving device connected to one of said line sections, a source of alternating current connected periodically to the other line section, a rectifier blocking the transmission of current in one direction over said line from said source to said device, and means for reversing said rectifier at least once during each period said source is connected to the line.

10 14. In a signalling system, a signalling line including two inductively associated line sections, a source of alternating current connected periodically to one of the line sections, a rectifier connected to said line and substantially blocking the transmission of either the positive or the negative portion of said alternating current over said line depending upon the sense in which said rectifier is connected to the line, means for reversing the sense in which said rectifier is connected to said line at least once during each period said source is connected to said line, and a pair of direct current devices connected to the second line section, one responding to the positive portion of the alternating current when that portion is transmitted over the line and the other responding to the negative portion of the alternating current when that portion is transmitted over the line.

15 15. In a signalling system as claimed in claim 14, wherein said direct current devices are connected in series across said second line section, a pair of rectifiers each bridging one of said devices, said rectifiers forming a series circuit across said second line section in which circuit said rectifiers are oppositely poled.

20 16. In a telephone system, a trunk line, an outgoing relay set at one end of the trunk line, means for seizing said relay set over any of a plurality of paths, means for generating alternating current,

means for blocking the transmission of either the positive or the negative portion of said alternating current, and means operative responsive to seizure of the relay set to control said last two means to transmit an impulse over the trunk line, said impulse comprising the positive portion only or the negative portion only of said alternating current depending upon the path over which said relay set was seized.

25 17. In a telephone system, a trunk line, an outgoing relay set at one end of the trunk line, means for seizing said relay set over any of a plurality of paths, means for generating alternating current, means for blocking the transmission of either the positive or the negative portion of said alternating current, and means operative responsive to seizure of the relay set to control said last two means to transmit an impulse over the trunk line, said impulse comprising alternating current generated by said second means or pulsating direct current derived from said alternating current, depending upon the path over which said relay set was seized.

30 18. In a telephone system, a trunk line, an outgoing relay set at one end of the trunk line, means for seizing said relay set over any of a plurality of paths, means for generating alternating current, means for blocking the transmission of either the positive or the negative portion of said alternating current, and means operative responsive to seizure of the relay set to control said last two means to transmit an impulse over the trunk line, said impulse comprising either the positive portion of the current generated by said second means for an interval of time followed by the negative portion of the current generative by said second means for an interval of time, or the negative portion of the current generated by said second means for an interval of time followed by the positive portion of the current generated by said second means for an interval of time, depending upon the path over which said relay set was seized.

35 40 HERBERT TÖPFER.
